(57) **CLAIM**

The ornamental design for a display screen or a portion thereof with a graphical user interface as shown and described herein.

DESCRIPTION

FIG. 1 is a front view of a display screen or a portion thereof with a graphical user interface showing a first embodiment of my new design.

FIG. 2 is a front view of a display screen or a portion thereof with a graphical user interface showing a second embodiment of my new design.

FIG. 3 is a front view of a display screen or a portion thereof with a graphical user interface showing a third embodiment of my new design.

FIG. 4 is a front view of a display screen or a portion thereof with a graphical user interface showing a fourth embodiment of my new design; and,

FIG. 5 is a front view of a display screen or a portion thereof with a graphical user interface showing a fifth embodiment of my new design.

The dashed broken line perimeter in the drawings illustrate a display screen or portion thereof and forms no part of the claimed design. The remaining dashed broken lines in the drawings illustrate portions of the graphical user interface that form no part of the claimed design.
